UNITED STATES PATENT OFFICE

102,742

DESIGN FOR A PLATE OR SIMILAR ARTICLE

Edgar Mott Bottome, Moundsville, W. Va., assignor to Fostoria Glass Company, Moundsville, W. Va., a corporation of West Virginia

Application November 17, 1936, Serial No. 65,979

Term of patent 3½ years

To all whom it may concern:

Be it known that I, Edgar Mott Bottome, a citizen of the United States of America, and a resident of Moundsville, county of Marshall, and State of West Virginia, have invented a new, original, and ornamental Design for a Plate or Similar Article, of which the following is a specification, reference being had to the accompanying drawing, in which—

Figure 1 is a bottom plan view of a plate or similar article, showing my new design; and—

Figure 2 is a section taken on line 2—2 of Fig. 2.

The upper surface is smooth, and the configuration of the lower surface is visible therethrough when made of transparent material.

I claim—

The ornamental design for a plate or similar article, substantially as shown and described.

EDGAR MOTT BOTTOME.
